INFOLDING OF VEST POCKET WELTS AND
THE LIKE

Alfred G. Gilbert, South Acton, Mass., assignor
to Reece Folding Machine Company, East
Cambridge, Mass., a corporation of Maine

Application September 13, 1939, Serial No. 294,636

1 Claim. (Cl. 223—38)

This invention relates to the infolding of vest pocket welts or other blanks of woolen or similar goods, and comprises apparatus adapted for the simultaneous infolding of a set of welt blanks to form the pocket facings for a vest or waistcoat, or similar garment, and method of folding and fixing the same preparatory to subsequent stitching thereof.

This subject presents special difficulties and problems due to the existing conditions in the practical manufacture of vests, composed usually of woolen goods or suiting of similar material, difficult to fold, press and handle. In the usual vest there are left and right hand upper and lower pockets, and a corresponding number of pocket welts, all four of which are of different form. This is due to the fact that the lower pockets are usually longer than the upper, while the inclines of the pockets, and therefore the angles of the folded ends of the welts, are the reverse of each other at the left and right sides. While a set of two pocket welts may sometimes meet the requirements of certain products, the customary vest has the four pockets as mentioned and therefore requires a set of four different welts, which may be enumerated as the left hand and right hand upper welts and the left hand and right hand lower welts, somewhat longer than the upper welts. In any given plant the difference in length between the upper welts and the lower welts, for example one half inch, is usually a uniform differential throughout the range of sizes of vests and pockets. On account of the necessity of matching the goods of the welts with the goods of the vest it is highly desirable that a complete set of the four welts be infolded and pressed and handled simultaneously, each set being temporarily attached or pinned to its vest, preparatory to the sewing thereof, thus saving matching complications and insuring a correct final product or garment.

A general object of the present invention is to afford uniformity of accuracy in the infolding and pressing or creasing of the folds of the welts of each set. Another object is to enhance convenience and reliability of production of welts and to increase the rate of output thereof and materially reduce the production costs. A particular object is to enable the entire set of welts for a single vest to be folded and creased in a single machine in a single operation, thus enhancing the other advantages enumerated. An additional object is to avoid the prevailing difficulties in regard to the creasing of the welt folds as formed and to cause them to remain folded

and creased until they have been stitched into the product or vest. Heretofore a scheme known as soaping has been used, which is undesirable, and the present invention is intended to dispense with the need of soaping, and the need of supplemental hand pressing of the folds, frequently practised, or the corrugating of the folds in the machine, all of which are disadvantageous; the present invention providing for the sticking together of the material at the folds without the need of adhesive, thus turning out a better folded and creased product and materially facilitating and speeding up the stitching operations. Among further objects of the invention is the quick adaptability of the machine to adjustment for change of size, to afford larger or smaller pockets according to the size of the garment, this being herein accomplished in a simple manner, preserving the size differential between the upper and lower pocket welts already mentioned. Other advantages of the invention will be explained in the hereinafter following description of an illustrative embodiment thereof or will be understood by those conversant with the subject. To the accomplishment of the objects and advantages mentioned the present invention consists in the novel method, system and apparatus for the infolding of vest pocket welt blanks, and the novel features of operation, combination, construction and arrangement herein illustrated or described.

In the accompanying drawings Fig. 1 is a front elevation view of a vest showing the upper and lower, right and left welts, all different either in size or shape.

Fig. 2 is a right end elevation of the upper portion of a welt infolding machine embodying the present invention, with the multiple defining member or templet shown in raised position above the folding bed of the machine.

Fig. 3 is a partial right hand elevation taken partly in vertical section.

Fig. 4 is a top plan view of the infolding bed or blank supporting portion of the machine and the edge infolding members thereon.

Fig. 5 is a face view of one of the unfolded cloth blanks, particularly the upper right welt blank, in its original cut condition, the subsequent fold lines being indicated in dotted lines; while Fig. 5a is a similar view of the same blank after its infolding and pressing.

Fig. 6 on a larger scale than Fig. 4 is a top plan view of the bed, with the welt blanks thereon, and the infolders and templet, the templet being shown with its upper or carrier portions broken

off, in the manner shown in Fig. 7, in order to afford a more complete view of the parts therebeneath; also the infolders are shown moved in, and the templet members retracted inwardly from the folds.

Fig. 7 is a vertical sectional view taken on the section line 7—7 of Fig. 6, looking from the front.

Figs. 8 and 9, also in vertical sectional view on the line 7—7 of Fig. 6, are partial views on a larger scale showing the relations of the bed, the infolders and the templet at different stages of operation.

Instances of automatic machines for the infolding and fold pressing of various fabric blanks include the Reece-type machines shown in prior patents such as Dixon 956,950 of May 3, 1910, Dixon 1,979,872 of November 6, 1934, and Gilbert 2,059,335 of November 3, 1936; and see also Reece 972,916, and Dixon 1,797,641.

The raw materials and product are designated by reference letters; the parts of the machine by reference numbers. The two upper welts or their blanks A comprise the upper right hand welt A₁ and the upper left hand welt A₂, while the lower welts B comprise the lower right welt B₁ and the lower left welt B₂. These are so shown on Fig. 5 illustrating a vest, and appear as well on Figs. 6 to 11. Fig. 10 shows the unfolded blank A₁, as an example, on which is indicated the line C of the fold to be produced, beyond which is the narrow margin D to be infolded; while Fig. 11 shows the margin D infolded, producing the finally folded and creased edge E. The long side edges of the blank A₁ are shown parallel, while the ends are cut on the bias of the woven material. The end slants of the welts A₁ and B₁ are usually the same and these are in the opposite direction to the slants of the other two welts. In the finished product the slanting ends frequently stand vertical, since the opening of each pocket, and the position of its welt, are usually at a substantial slant to the horizontal.

The machine may comprise an upright frame 18, upon the top elements 19 of which is mounted the blank support or bed 29, on the central area 21 of which the blanks are to be laid, defined, folded and creased. The bed is hollow and steam heated by steam chest 22, suitably supplied, and its top plate or pad 24, on which the blanks rest, may be formed with steam passages, as will be described. The bed area is large enough to receive the multiple set of blanks laid out in series, as Fig. 6 shows, between the infolders. On account of the use of released steam the working parts should be of plated or other rust proof metal.

The upper rear portion of the frame supports an upstanding bracket 24 on which is swingingly mounted a templet carrying arm or arms 25, between which may be provided a lamp 26 for illuminating the bed to assist the positioning of the blanks. The templet will be subsequently described. Below the bed may be conventional shafting and connections, not herein shown, to actuate templet, infolders and pressing means on the principles disclosed in said patents. If the cycle is 12 seconds, 300 complete sets can be completed per hour; with but little attention besides feeding in the blanks of each set, from a supply, and collecting each set for pinning to a vest, thus avoiding the prevailing hindrances from hand soaping and pressing, and facilitating the sewing in various ways including the avoid-

ance of thread breakage incurred in the use of soaped welts.

The infolding means is shown as comprising two opposite infolders, a left hand infolder comprising a body 35 with infolding plate 36 extending inwardly therefrom and a right hand infolder 38 with similar inward plate 39. Each of the infolders has its body formed with a hollow chamber 41 by which it may be steam heated to improve the folding and pressing actions. The two infolders are simultaneously movable inward toward each other to fold the blank edges over the edges of the defining templet to be described, and the direction of infolder sliding movement will be termed longitudinal for purposes of description. The infolding plates have specially shaped folding edges as will be described, oppositely arranged at the left and right. The four blanks A₁, A₂, B₁ and B₂ are all different in shape or size and Fig. 6 shows how they may be laid out on the bed, with their long edges longitudinal and their inclined ends in suitable relation to the templet and folding members. Fig. 8 shows the retracted or outward position of the infolder 36, spaced slightly outwardly from the defining edge of the templet. This permits the blank to be set in place, with its end margin D overlying or at least upstanding against the inner edge of the infolder, so that when the infolder moves inwardly, to the right in Fig. 8, with preferably an accompanying rise, the parts come to the position shown in Fig. 9, the fold being still occupied by the edge of the templet. The position of the parts after the subsequent retraction of the templet plates is indicated in Figs. 6 and 7, in which position the infolders may be pulled forcibly downward, or conversely the bed lifted, to squeeze and sharply crease the intervening folds. In this connection an expedient will be described to cause the folds to be sharply and permanently creased so as to retain their position until the subsequent stitching operations.

The four welt blanks being arranged as shown in Fig. 6, or in any convenient different sequence, the infolders are correspondingly constructed and shaped, for example as follows. The defining part of each infolder is laterally of sufficient length to operate upon all four of the blanks separately but simultaneously. For example the left hand infolder plate 36 has four edge sections, each of which is straight, but appropriately slanted, and the total of the four sections taking for example a zigzag contour. Thus the left hand infolder has a straight edge section 43 for the left end of the blank A₁ and the right infolder has a corresponding section 43R for the other end of the same blank. These opposite infolder edges or sections therefore are parallel and complementary. Their slants correspond with the end slants of the blank and are inclined to the inward or longitudinal folding movements of the infolders. For the next blank A₂ the respective left hand and right hand infolders have the edge sections 44 and 44R, in this case slanted oppositely to the slant of the sections 43 and 43R. For the third blank B₁ the respective infolders have the inclined folding sections 45 and 45R, the series being completed by the folding sections 46 and 46R near the front ends of the respective infolder plates 36 and 39. Therefore, by a simple mutual approaching movement the two infolders attend fully to the infolding of both ends of all of the blanks constituting a complete set of vest welts.

A particular feature will be noted in that the first and second pairs of infolding edges are for the shorter blanks, the remaining two being for the longer blanks, pursuant to which, to give the necessary differential of length, there is a substantial offset in the contour or contours, for example as shown at 47 near the central part of the right hand infolder plate 39; although this offset could as well be at the other side, or split between the two sides, as shown.

In order that the infolder system may have rising and lowering movements the infolders 35 and 38 are mounted, not directly upon the fixed bed 20 of the machine, but upon a carrying means in the form of a hollow frame 48 comprising front and rear side bars between which the two infolders may slide longitudinally, a pair of holdown strips 49 being shown, overlying the thinned edges of the infolders, as best seen in Figs. 2 and 3, to confine them on the frame 48 while permitting their inward and outward sliding movements. To bring about the upward and downward movements of the frame and infolders conventional means may be used or this may be done by hand or foot in a manner known in the art, so that, by the preferred operation the infolders are lifted slightly during their inward movements from the position of Fig. 8 to that of Fig. 9, and subsequently are pulled forcibly downward in order to squeeze and crease firmly the folds when in the position shown in Figs. 6 and 7.

The simultaneous inward and outward movements of the two infolders may be conventionally performed, for example, by means provided at each end of the machine including an upright lever 53, centrally pivoted, extending upwardly to the infolder at that end. The top of each lever 53 is articulated to the infolder by a fixture 55 secured in a slot 56 formed in the infolder. The fixture at the right hand side is provided with a clamping handle 57. By this means adjustment for different sizes of welt may readily be effected by simply loosening the fixture 55 by the handle 57, which may be done at the right hand side only, thereupon shifting the infolder position in relation to the top of its actuating lever 53 and then reclamping the fixture. This adjusting operation may be greatly facilitated by providing a scale 53 to which the infolder may be set, as shown in Fig. 4. The adjustment to welts of different size is thus effected without changing the one-half inch or other differential between the lengths of the welts for the upper and lower pockets respectively. Welt lengths range from 2½ to 6 inches and a machine may be adjustable to this full range, or a part of it.

Referring next to the templet or defining member it may comprise a stock or templet body 60 mounted at the free ends of the swinging arms 25. Underneath the templet body, see Figs. 2, 6 and 7, is a left hand carrier 61 carrying a thin templet plate or definer 62, and a right hand carrier 64 with a definer 65. Each of the carriers may have a hollow portion to receive steam, or be otherwise heated; an advantage of maintaining in hot condition the bed, the infolders and the templet, being to prevent or minimize condensation upon and possible dripping of moisture from these elements due to the presence of released steam as will be described. The two carriers are arranged to engage and slide longitudinally along in the templet body, preferably with simultaneous outward and inward movements

of the carriers and definers, effected conventionally or by a handle 79. The templet may be bodily swung down to the work and later elevated about the fulcrum of the arms 25 by any means, as manually.

Each of the two plates of the templet has a special contour which agrees substantially with the described contours of the two infolder plates 36 and 39. Thus the left hand templet plate 62 10 has an edge section 73 corresponding to the edge section 43 of the left hand infolder and to the left end of the first welt blank A1. Oppositely the templet plate 65 has a corresponding edge section 73R. To abbreviate the description, the plates of the templet are formed further with edge sections 74 and 74R, 75 and 75R and 76 and 76R corresponding with the similar sections of the infolder plates, with an offset or offsets 77 corresponding with the offset 47 in the infolder plate 39.

In order to fix the folds or creases so as to retain their condition until the later sewing has been performed the following means may be employed. This operates by applying steam, releasing it in the form of a spray or jets, along each of the folded edges in a manner to permeate the fabric and moisten it, both through the body of the welt and its infold, this being done after the templet has withdrawn from the folds and 20 during the actual pressing or squeezing of the folds between the infolders and bed. When performed in this manner, the blank body and fold being squeezed forcibly against each other, while moist, it is found that sufficient fixing or adhesion is secured to dispense with the application of an adhesive medium, heretofore tried but subject to objections.

To carry out this part of the invention the bed 20 and its central area 21 are shown as provided with steam passages 83 arranged to conduct steam to a series of apertures 84 which are directed upwardly and deliver jets directly into the body of the blank adjacent to the length of each of the folds while confined between the bed and the infolder. The steam release might equally well be applied from above through the infolder but underneath application is preferred. A supply passage 85 is shown conducting steam to the passages 83, and in turn, an exterior pipe 50 86 is shown leading from a steam supply to the passage 85.

It is desirable to release a relatively brief application of steam, during the period of the squeezing of the folds, and to cut off the steam before the pressing is discontinued, so that the fabric may be pressed while moist, and dried under the heat before the pressure is relaxed, this operation affording a very effective mode of fixing and creasing the folds. For these purposes a steam valve 87 is shown interposed in the supply pipe 86, the valve having a lever 88 for opening and closing it. These operations are preferably performed automatically in time with the other operations, and for briefly opening and closing their valve there is shown a connecting rod 89 vertically slidably, its lower end having a follower which rests upon the periphery of a cam 90. The cam has a short rise or button 91 adapted to cause a momentary lifting and dropping of the connecting rod, and the cam is mounted on a shaft 92, a spring 93 restoring the connecting rod and valve lever to closed position when released by the cam. These parts may be manually or otherwise so operated that the valve 70 75 is opened preferably at the instant the squeezing

pressure is applied, promptly closing so that the moistened fabric may be dried between the bed and infolders before the squeezing pressure is relaxed.

The steam spraying valve is normally closed. When opened the steam is applied internally to the fabric adjacent to each fold, through one of the members, the bed or the infolder, preferably upwardly through the bed as described; the infolder acting as a baffle operating to spread the steam laterally through the fabric, softening and loosening the fibers and so conditioning the same as to promote interengaging between the faces of the blank body and folded margin across the width of the fold and thus assisting the fold to remain closed, besides sharpening and setting the extreme edge of the crease or fold itself.

In the art of manufacturing vests or like garments the method of the present invention may be reviewed as follows. It is the method or system of quantity preparation of sets of differing welts for sewing to the vests or other garments, and comprises the handling, the folding and the creasing of the welts of each set thereof substantially as follows. The cut fabric blanks for the one set of welts are laid out in serial arrangement or general alinement, as upon a folding bed. The folds at the ends of all of the blanks of the set are then simultaneously defined and thereupon are simultaneously infolded, and held in such condition. Upon the withdrawing of the defining means the blank folds are left held directly in contact upon the bodies of the blanks resting on the bed. The squeezing pressure is then applied upon the folds to crease them firmly. When the material is such that the folds are difficult to crease steam is now applied in quantity to moisten the fabric and permeate it adjacent to the folded edges while under the squeezing pressure, this step giving the result that adherence is produced between the fabric body and its folds, thus fixing them until later sewed. Finally the folded and creased welts are removed and collected from the bed as a set and are pinned or otherwise clipped to the vest or garment preparatory to being stitched thereon. As already indicated the release of the moistening steam is begun about or before the creasing pressure is applied and preferably terminated by cutting off the steam before 50

releasing the pressure. The operating parts are maintained hot so that the creases quickly become dry, or substantially so, before the pressure is removed.

5 This application is a continuation in part of copending application Serial No. 217,860, filed July 7, 1938, for Machine and method for folding and fixing fabric blanks.

10 There has thus been described a means, system and method for the infolding of vest pocket welts and the like, embodying the principles of the present invention and attaining the objects thereof. Since many matters of operation, combination, construction and arrangement may be 15 variously modified without departing from the principles hereof it is not intended to limit the invention to such matters except so far as set forth in the appended claim.

What is claimed is:

- 20 In the art of manufacturing vests or like woolen garments the method of quantity preparation of sets of differing welts for sewing to vests or other garments, comprising the handling, folding and fixing of the woolen welts of each set thereof as follows: spreading out the cut fabric blanks for one set of welts in general alinement upon a smooth folding bed, defining simultaneously the folds at the ends of all such blanks of the one set, infolding simultaneously 25 all such ends as so defined and then holding them so, and withdrawing the defining means to leave the blank infolds held directly in contact upon the blank bodies resting on the bed beneath the infolding means; then applying 30 heavy squeezing pressure to crease such folds while remaining unoccupied between the bed and infolding means, while maintaining heated both the supporting bed and infolders, applying steam to such folds in a short discharge to 35 moisten the fabric and permeate both the body and infold adjacent to the folded edges while in direct face contact under squeezing pressure, thereby to cause face adherence between fabric body and folds and to fix the creases until later sewed, without need of adhesive; and removing and collecting the set of folded and fixed welts and clipping the set together for its garment 40 preparatory to stitching the welts to the garment.

ALFRED G. GILBERT.
